CALK GUN

Samuel Crewe, East Cleveland, Ohio

Application April 5, 1940, Serial No. 328,065

17 Claims. (Cl. 74—169)

This invention relates to calk guns and particularly to the ratchet mechanisms in them which operate the piston, and is another form of the device shown in the Patent No. 2,180,978 which was granted to me on November 21, 1939.

The primary objects of the instant invention are substantially the same as those set forth in the aforesaid earlier patent; but in addition thereto, this invention provides a mechanism which has an automatic ratchet release which goes into operation when the manually operated parts are abnormally closed or squeezed rather than when abnormally opened or released. Some operators prefer this reverse operation because for certain types of work this improved modified device has a tendency to prevent or forestall fatigue.

Another object of this invention is to provide for the use of a round, rotatable ratchet-bar, the teeth of which may be entirely disassociated from the driving mechanism regardless of the relative positions of the operating lever and handle members.

These and other objects and features of the invention will become apparent from a study of the following description and claims together with the accompanying drawing in which like parts are designated by like reference characters and wherein:

30 Figure 1 is a side elevation of a calking gun, parts of which are broken away to show details of construction and which indicates the normal position of the ratchet mechanism parts;

Figure 2 is a cross-sectional view of the ratchet mechanism taken along the lines and in the direction of the arrows 2—2 of the Figure 1;

Figure 3 is a cross-sectional view of the same mechanism taken along the lines and in the direction of the arrows 3—3 of the Figure 1;

40 Figure 4 is a side view of the ratchet mechanism showing relative positions of the various elements when the ratchet-bar has been moved forward from the position shown in the Figure 1 and is about to become stationary and ready for another projecting operation;

Figure 5 is a side view of the same mechanism showing position of the parts when the ratchet is automatically disengaged from the pawl and dog members;

50 Figure 6 is a sectional view similar to that of the Figure 3 but showing the round ratchet-bar turned half way around thus isolating the teeth thereon from the pawl and dog elements; and

Figure 7 is a side view of a modified form of 55 the invention showing the automatic dog op-

erating arm connected to the pawl member instead of directly onto the operating lever.

Broadly this invention consists of a barrel 10, a nozzle 11 on the forward end of the barrel and the ratchet mechanism on the rear end of the barrel. Both the barrel and the nozzle have been specifically described in my prior patent heretofore referred to.

The ratchet mechanism as shown which forms one of many embodiments of the invention, consists of a handle member 20, an operating lever 30, a serrated ratchet-bar 40 and pawl and dog members 50 and 60 respectively. Each of these members will be described in detail and in the order just mentioned.

10 The handle member 20 is made of sheet metal, formed hollow and with side walls 21 and 22, a top portion 23 and a rear wall 24. The lower portion of the side walls 21 and 22 and rear wall 24 are shaped to serve as a suitable grip element 20 15 25. The forward end of the handle member 20 has attached thereto a cup 26 which has a conventional means for engaging the barrel 10.

The upper portion of the rear wall 24 is provided with a round hole 27 which is aligned with the axis of the barrel 10 and through which the ratchet-bar 40 may move freely. The center of the cup 26 is simultaneously provided with a hole 28 which permits the free passage of the ratchet-bar 40 into and out of the barrel 10. A small 30 concave roller bearing 29 is mounted between the walls 21 and 22 to facilitate the movement of the ratchet-bar 40 through the handle chamber and which prevents uneven wear and strain on the piston element 12 and the portion of the handle member adjacent the holes 27 and 28. This handle member is made smooth with rounded wall corners and without sharp edges or unnecessary projections extending therefrom.

40 The operating lever 30 is also made of sheet metal and is substantially U-shaped in cross section. It is pivoted to the handle member by the primary pivot pin 31. The lower arm of the lever, the portion below the pin 31, is shaped to form a reciprocating grip element 32 and which 45 opens or closes with respect to the grip element 25. A simple expansion spring is supported between the two grip elements 25 and 32 so as to separate them as far as possible. This separated position, as shown in the Figure 1, is the normal 50 position of the grip elements.

The upper portion 33 of the operating lever is provided with a pawl member 50 herein-after described in detail. The upper arm 33 is also provided with a small expansion spring 35 55

which serves to normally retain the pawl member 50 in engagement with or in ready contact with the ratchet-bar 40. The top of the arm 33 is always below the ratchet-bar 40 and in no way does it interfere with its free movement.

The ratchet-bar 40 is simply a length of round rod threaded on one end to engage the piston element 12 and drilled laterally at its opposite end to receive the simple cross-bar 41 which serves as a grip to facilitate convenient manipulation or rotation of the bar. A straight line of evenly spaced and regularly shaped teeth 42 are formed on the bar between the piston element 12 and the cross-bar 41. These serrations or teeth 42 face downward and are normally in engagement with the pawl and dog members 50 and 60 respectively.

Each tooth on the ratchet-bar has an inclined side and a perpendicular side and the device is assembled so that the inclined side faces forward and the perpendicular side faces rearward. This assembly allows the ratchet-bar to readily move forward and past the pawl and dog members but not rearwardly thereof unless the pawl and dog members are disengaged or isolated therefrom.

The pawl member 50 is a piece of metal or other suitable material shaped as shown in the drawing. Its rear end 51 has the secondary pivot pin 34 which engages the operating lever. The upper and forward corner of this element 50 is acutely pointed to form a detent 52 for the specific engagement of the teeth 42 of the ratchet-bar.

Integral with the pawl element 50 and depending below the detent at a slight angle, there is a trip finger 53 which is also referred to herein as a trigger. The bottom surface of the pawl member 50, the portion between the trigger 53 and the rear end 51, is in constant engagement with the small expansion spring 35 which is carried by the operating lever.

A small pin 54 is mounted on the walls 21 and 22 of the handle member, which pin extends laterally through the hollow chamber and is in a position which will bar the continued movement of the trigger 53 when the grip elements 25 and 32 are squeezed closer together than is normally necessary to cause the pawl member 50 to advance the ratchet-bar a predetermined definite distance.

The dog member 60 is made of a material similar to that of the pawl member 50 and is shaped substantially as shown in the drawing. Its lower and rearward end is pivoted laterally to the handle member 20 by means of the pin 61. Its upper and forward end is pointed to form a detent which is herein referred to as the pick 62 and which engages the teeth 42 of the ratchet-bar. A small expansion spring 67 is mounted in a conventional manner on the pin 61 so as to keep the pick 62 in normal and constant engagement with the ratchet-bar 40.

A second pin 63 which has a somewhat flattened and wider head 64 is attached to the dog member 60 above the pivot pin 61 and approximately in longitudinal alignment with the secondary pivot pin 34 of the operating lever.

A simple flat arm 65, made of a piece of stiff metal extending practically parallel with the ratchet-bar 40, connects either the dog and operating lever or the dog and pawl members and coordinates their respective movements so that the dog and pawl members may be simultaneously disengaged from the ratchet-bar.

The forward end of the arm 65 has a longitudinal slot 66 through which the pin 63 may freely slide. The head 64 of this pin retains the arm in

position at all times and prevents the pin from becoming disengaged from the slot. The rear end of the automatic release arm 65 has a small hole which accommodates either the secondary pivot pin 34 or the pin 55 which is attached to the pawl member just below the detent 52. The preferred form of linkage is shown in the Figures 1 to 6 while the modified assembly is shown in the Figure 7.

For normal operation, that is when it is desired to project the piston and the ratchet-bar forward, the arm 65 has no effect on the dog element. The pawl and dog elements are then interdependent and react or function in the conventional manner. The Patent No. 2,115,591 to Sherbondy for a Gun for discharging plastic compositions which was granted April 26, 1933 shows an assembly of a conventional dog and pawl which are not coupled to form an automatic release.

It is only when the operator desires to release the compression of the plastic material in the barrel that the grip elements 25 and 32 are brought together closer than otherwise. During normal operation the operating lever 30 moves between the positions indicated in full lines of the Figure 1 and the alternate position indicated in broken lines and by the character 30a of the same figure. When the automatic release is in operation, the operating lever takes the alternate position indicated by the broken lines and the character 30b which position is like that shown more clearly in Figure 5.

When the lever is moved rearward of the position 30a, the trigger 53 is stopped by the trip pin 54. The upper part of the operating lever 30 and the pawl 50, however, continue to move forward but the detent 52 is deflected downward and is taken out of engagement with the ratchet-bar teeth 42. In either of the forms shown the automatic release arm 65 continues to move forward with the forward movement of the arm 33 and when the pin 63 reaches the rear end of the slot 66, the pick 62 is similarly disengaged from the ratchet-bar. By properly positioning the trip pin 54 or by properly sizing the slot 66, the pawl and dog members may be made to engage or disengage the ratchet-bar simultaneously and very smoothly.

In order to refill the barrel 10 with material, it becomes necessary to draw the ratchet-bar to the rear as far as possible which is its normal initial position. This may be done by either disengaging the ratchet-bar from the driving mechanism by bringing the automatic release into operation and then drawing the bar back; or it may be accomplished by disassociating the operating parts by simply turning the rod 180° by means of the grip element 41 and drawing it back. The latter method may, in some instances, be preferred because it also acts as a safety lock and prevents accidental or unwarranted ejection of material regardless of the relative movements of the grip elements 25 and 32.

It should be noted however that this ratchet mechanism, unlike similar mechanisms of the prior art, does not permit the movement of the ratchet-rod by any other means than by the operation of the grip elements when the teeth 42 are pointed downwardly and in their normal positions. In other devices the ratchet-rod may be moved forward by simply pushing on the grip element 41 when the pawl and dog are in normal position. The particular design of the pawl member of this invention does not permit such forward movement except when the operating

lever is taken out of its normal position. Attempting to so move the ratchet-bar without simultaneously moving the operating lever, will tend to drive the detent 52 downward; but as the 5 detent goes down, the trigger 53 moves back and strikes the primary pivot pin 31 before the detent 52 clears the teeth 42 sufficiently to become disengaged therefrom. This feature is particularly 10 advantageous to prevent unnecessary ejection of material, if the gun happens to be dropped in a manner tending to project the ratchet-bar forward.

Among the many advantages this type of gun has over the prior art devices; one advantage is, 15 that the friction and wear of the automatic release sliding parts will not so quickly interfere with the proper operation of the apparatus; and another is, that the various expansion springs used in the device need not be in as fine a balance 20 as is required otherwise.

It will now be clear that there is provided by this invention a calk gun which accomplishes the objects originally set forth. While the invention has been illustrated and described in two forms, 25 it is to be understood that the embodiment of the invention as set forth is suggestive only and is not to be considered in a limiting sense. It is to be further understood that there may be other forms or adaptations of the invention and those 30 modifications are also considered to be within the broad scope of the invention as no limitations upon it are intended other than those imposed thereon by the appended claims.

I claim:

1. A ratchet mechanism, comprising in combination, a handle member, an operating lever pivoted to the handle member, a ratchet-bar movable through the handle member, a pawl member mounted on the operating lever engageable with the ratchet-bar, a dog member mounted on the handle member engageable with the ratchet-bar, and a slotted arm on the lever member for disengaging the said dog member.

2. A ratchet mechanism, comprising in combination, a handle member, an operating lever pivoted to the handle member, a ratchet-bar movable through the handle member, a pawl member including a tension means pivoted on the operating lever engageable with the ratchet-bar, a dog member pivoted on the handle member engageable with the ratchet-bar, and a slotted arm on the pawl member for disengaging the said dog member.

3. A ratchet mechanism, comprising in combination, a handle member, a trip pin mounted in the handle member, an operating lever pivoted to the handle member, a ratchet-bar movable through the handle member, a pawl member mounted on the operating lever engageable with the ratchet-bar, a trip finger integral with the pawl member actuated by the said trip pin for disengaging the said pawl member from the ratchet-bar, a dog member mounted on the handle member engageable with the ratchet-bar, and an arm connected to the operating lever and mounted on the dog member for disengaging the dog member from the ratchet-bar simultaneously with the actuation of the said trip pin.

4. A ratchet mechanism, comprising in combination, a handle member having a trip pin mounted therein, an operating lever pivoted to the handle member, a ratchet-bar movable through the handle member, a pawl member having a trip finger actuated by the said trip pin

mounted on the operating lever engageable with the ratchet-bar, a dog member mounted on the handle member engageable with the ratchet-bar, and an arm member connected to the operating lever and mounted on the dog member for disengaging the said dog member from the said ratchet-bar.

5. A ratchet mechanism, comprising in combination, a handle member having a trip pin mounted therein, an operating lever pivoted to the handle member, a ratchet-bar movable through the handle member above the operating lever, a pawl member pivoted to the operating lever engageable with the said ratchet-bar, the said pawl member having a trip finger thereon actuated by the said trip pin, a dog member including a tension means pivoted to the handle member below the said ratchet-bar and engageable therewith, and an arm connected to the operating lever and mounted on the dog member for disengaging the dog member from the ratchet-bar simultaneously with the actuation of the said trip finger by the said trip pin.

6. A device of the type defined in claim 5 and further characterized by having a tension means carried by the operating lever engaging the pawl member with the ratchet-bar.

7. A ratchet mechanism, comprising in combination, a handle member, an operating lever pivoted to the handle member, a ratchet-bar movable through the handle member, a pawl member pivoted to the operating lever engageable with the ratchet-bar, a tension means carried by the operating lever engaging the pawl member with the ratchet-bar, a dog member pivoted to the handle member engageable with the ratchet-bar, and an arm member connected to the operating lever and mounted on the dog member for disengaging the said dog member from the said ratchet-bar.

8. A ratchet mechanism, comprising in combination, a handle member, an operating lever pivoted to the handle member, a ratchet-bar movable through the handle member, a pawl member pivoted to the operating lever engageable with the ratchet-bar, a tension means carried by the operating lever engaging the pawl member with the ratchet-bar, a dog member pivoted to the handle member engageable with the ratchet-bar, and a slotted arm member connected to the pawl member and mounted on the dog member for disengaging the said dog member from the said ratchet-bar.

9. A ratchet mechanism, comprising in combination, a handle member, an operating lever pivoted to the handle member, a ratchet-bar movable through the handle member, a pawl member mounted on the operating lever engageable with the ratchet-bar, a dog member pivoted on the handle member engageable with the ratchet-bar, the said dog member having a pin thereon, and an arm member having a slot therein connected to the operating lever and engaged by the said pin for disengaging the said dog member from the said ratchet-bar.

10. A ratchet mechanism, comprising in combination, a handle member, an operating lever pivoted to the handle member, a ratchet-bar movable through the handle member, a pawl member pivoted to the operating lever engageable with the ratchet-bar, a tension means carried by the operating lever engaging the pawl member with the ratchet-bar, a dog member pivoted on the handle member engageable with the ratchet-bar, the said dog member having a

- pin thereon, and an arm member having a slot therein connected to the operating lever and engaged by the said pin for disengaging the said dog member from the said ratchet-bar.
5. 11. A ratchet mechanism, comprising in combination, a handle member, an operating lever pivoted to the handle member, a ratchet-bar movable through the handle member, a pawl member pivoted to the operating lever engageable with the ratchet-bar, a tension means carried by the operating lever engaging the pawl member with the ratchet-bar, a dog member pivoted on the handle member engageable with the ratchet-bar, the said dog member having a pin thereon, and an arm member having a slot therein engageable by the said dog member pin connected to the said pawl member and actuated thereby for disengaging the said dog member from the said ratchet-bar.
10. 12. A ratchet mechanism, comprising in combination, a handle member having a trip pin mounted therein, an operating lever mounted on the handle member, a ratchet-bar movable through the handle member, a pawl member mounted on the operating lever engageable with the said ratchet-bar, the said pawl member having a trigger thereon actuated by the said trip pin, a dog member mounted on the handle member engageable with the ratchet-bar, the said dog member having a pin thereon, and an arm member connected to the operating lever and actuating the said dog member, the said arm member having a slot therein engageable with the dog member pin in a manner causing the disengagement of the dog member from the ratchet-bar simultaneously with the actuation of the pawl member trigger by the said handle member trip pin.
13. A device of the class defined in claim 12 and further characterized by having a tension means carried by the operating lever engaging the pawl member with the ratchet-bar.
14. In a ratchet mechanism of the type having a pawl and a dog engageable with a serrated bar, a connecting link, consisting of, an arm having a means for pivotal engagement with the pawl at one end thereof, and a slot at the opposite end thereof for engagement with the dog.
15. A ratchet mechanism, comprising in combination, a handle member, an operating lever pivoted to the handle member, a ratchet-bar movable through the handle member, a pawl member mounted on the operating lever engageable with the ratchet-bar, a dog member mounted on the handle member engageable with the ratchet-bar, and a means on the said lever member for disengaging the dog member, the said dog member and the said means having a pin and 20 slot connection.
16. In a ratchet mechanism of the type having a pawl and a dog member engageable with a serrated bar, a connecting link member having one of its ends engageable with the dog member, one 25 of the said members having a pin and the other of the said members having a slot to receive the said pin.
17. In a ratchet mechanism of the type having a pawl and a dog member engageable with a serrated bar and a pivoted lever for moving the said bar, a link member movable with the said pivoted lever and engageable with the said dog member, one of the said members having a pin and the other of the said members having a slot engageable with the pin.

SAMUEL CREWE.
